(57) **CLAIM**

The ornamental design for a foldable ironing board with iron holder as shown and described.

DESCRIPTION

FIG. 1 is a rear, left, and top perspective view of a foldable ironing board with iron holder, showing my new design; FIG. 2 is a front, right, and bottom perspective view thereof; FIG. 3 is a front elevational view thereof; FIG. 4 is a rear elevational view thereof; FIG. 5 is a right side elevational view thereof; FIG. 6 is a left side elevational view thereof; FIG. 7 is a top plan view thereof; FIG. 8 is a bottom plan view thereof; FIG. 9 is a detailed view taken from the encircled portion labeled "9" in FIG. 1; and, FIG. 10 is a perspective view of the foldable ironing board with iron holder, illustrated in a folding state. The short-dash and long-dash broken lines in FIGS. 1 and 9 denote the boundaries of the detail areas and form no part of the claimed design. The even broken lines in the drawings depict portions of the foldable ironing board with iron holder that form no part of the claimed design.
